COIN-CONTROLLED SWITCHING MECHANISM

Application filed February 28, 1929. Serial No. 343,447.

The object of this invention is to provide a new and improved form of coin controlled apparatus by which an electrically operated mechanism may be started at will and automatically stopped at a given interval thereafter and by which a radio apparatus or any other suitable device may be intermittently operated.

Another object of the invention is to simplify the electric circuit and operating mechanism therefor so that there is little or no chance of their getting out of order.

Another object of the invention is to cheapen the cost of manufacture thereof and make the part strong which together with the simplicity thereof will enable the apparatus to withstand the customary abuse of slot machines.

These and other objects of the invention will be illustrated in the drawings, described in the specification and pointed out in the claims at the end thereof.

In the drawings:

Figure 1 is a diagrammatic view of the coin controlled mechanism and electric circuits and operating mechanism connected therewith.

Figure 2 is a diagrammatic view of a modified form of the switch and electro-magnet for closing the circuit.

Figure 3 is a top plan view of the gearing shown in Figure 1.

Figure 4 is a side elevation of the gear 13 looking at it from the right in Figure 3.

Figure 5 is a modified form of the rotating switch showing the contact pins carried on a separate disc.

In the drawings like reference numerals indicate like parts.

In the drawings reference numerals 1 and 2 indicate contacts which are joined together in the circuit by means of the convex conductor 3 which is mounted on the plate 4 pivoted at 5. When a coin of suitable size and weight is deposited on the plate 4, the plate is swung to the dotted line position wherein the contact 3 closes the circuit between the contacts 1 and 2. The conductor 6 coils around a bar making an electromagnet 7 which is energized when the circuit is

closed and this attracts and holds down the plate 4 into contact therewith until the circuit is broken in the manner that will presently be described.

The electric energy is derived from the ordinary 110 volt source, the mains being indicated at 8 and 9. From the electromagnet 7 the conductor 6 leads to a contact spring 10 which makes contact with the one or the other of the pins 11 and 12 carried on the gear wheel 13. This gear wheel 13 meshes with the gear wheel 13A which is carried on the same shaft with the worm wheel 14 which is driven by a worm 15 which in turn is driven by an armature 16 by means of the windings 17 and 18, this part of the apparatus being substantially the same as is ordinarily used in a watt-hour meter or a synchronous motor, the gears and contact switch being added thereto. The conductor 6 connects to the contact springs 10, pin 11 and shaft 15 with the conductor 19 which connects through the bearing 20 and conductor 21 to the main 9 which is also connected to the windings 17 and 18 of the motor. The main 8 is connected to one side of an electrical apparatus contained in the radio set or other device that is used and the main 9 is connected to the other side through the winding 17.

When the apparatus is started the circuit is closed at 1 and 2 and the armature 16 begins to rotate, and this in turn rotates the gears 14 and 13 and continues to rotate them until the pin 11 passes beyond the contact spring 10. The circuit is then interrupted and this de-energizes the electromagnet 7 which then releases the plate 4 which returns to the full line position keeping the circuit open until another coin is dropped, although in the meantime the contact spring 10 has come in contact with the pin 12 in which position it remains to cause the further operation of the mechanism as soon as another coin is dropped on the plate 4, to close the circuit between the contacts 1 and 2.

In Figure 2 we have shown a modified form of the switch in which the plate 4A is pivoted at 5A and is normally held up by

the spring 6A. This plate carries a contact 1A that touches the contact 2A and closes the circuit that energizes the electromagnet 7A. The balance of the circuit contacts and mechanism is otherwise the same as is shown in Figure 1.

In Figure 4 we have shown the gear 13 mounted on the supports 25 and 26. The shaft of the gear 13A is carried on the supports 27 and 28. The supports 25 and 26 for the shaft and the gear 14 also appear in Figure 4. In Fig. 5, instead of the arrangement shown in Figure 4 we substitute for the gear 13 a disc 30 which carries the pins 11 and 12. This gear is carried on a shaft 31 which rotates in the supports 32 and 33 and is driven by the gear 34 which in that case meshes with the gear 13A, the balance of the mechanism being otherwise the same.

20 The circuit controlled by this device will be used to operate a radio apparatus or any other suitable device and the length of time which it would be allowed to operate would be controlled by the gearing shown. This 25 time can be lengthened or shortened by changing the gears to secure this result. This time can also be lengthened or shortened by adjusting the magnetic flux passing through the armature 16 causing it to rotate 30 at a different rate of speed. In either of these ways a wide range of time during which the operation of the device is permitted may be secured.

We claim:

35 1. A coin controlled switching mechanism comprising a motor having an armature, a shaft on which said armature is mounted to rotate, a worm on said shaft, a worm gear driven thereby, a wheel driven from said 40 worm and gear train, pins carried on said wheel, a spring making contact with one or the other of said pins, to close and open auxiliary contacts, a shaft for said wheel, normally open auxiliary contacts in series with 45 said pin and spring, a coin operated switch for closing said circuit and causing said armature to rotate, an electromagnet in said circuit adapted to hold the switch in position to keep the circuit closed, said circuit being broken by the rotation of the wheel carrying one or the other of said pins out of 50 contact with said spring.

55 2. A coin controlled switching mechanism having two switches therein, a spring by which one of said switches is normally held open and the other of which is normally closed, an electromagnet in the circuit and adapted to be energized by the closing of 60 the first switch and to remain closed, a motor in series with the switches adapted after a predetermined time to operate the second named switch to open and again close it, thereby momentarily opening the circuit and deenergizing the magnet and permitting the

first named switch to be opened to break the circuit.

In testimony whereof we affix our signatures.

FLOYD L. COFFING. 70
